(57) **CLAIM**

The ornamental design for a personal safety indicator, as shown and described.

DESCRIPTION

Utility patent application of same applicant filed on the same date as this application and entitled, "Safety Indicator and Method" Ser. No. 11/255,609

FIG. 1 is a personal safety indicator shown in perspective.

FIG. 2 is a left side view of the portable personal safety indicator.

FIG. 3 is a right side view of the portable personal safety indicator.

FIG. 4 is a top view of the portable personal safety indicator.

FIG. 5 is a bottom view of the portable personal safety indicator.

FIG. 6 is a rear view of the portable personal safety indicator; and,

FIG. 7 is a front view of the portable personal safety indicator.

The broken line showing of letters and numbers are included for the purpose of illustrating non-claimed subject matters and forms no part of the claimed design.
